[57] CLAIM

The ornamental design for a model railroad track clamp, as shown and described.

DESCRIPTION

FIG. 1 is a top, front perspective view of a model railroad track clamp showing my new design, the broken line showing of the model railroad tracks and the top rear perspective of the model railroad clamp is for illustrative purposes only and forms no part of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left elevational view thereof.

FIG. 1

FIG. 2

FIG. 3
